UNITED STATES PATENT OFFICE.

NICHOLAS S. VEDDER AND FRANCIS RITCHIE, OF TROY, AND TOBIAS S. HEISTER, OF LANSINGBURG, ASSIGNEES TO NICHOLAS S. VEDDER, OF TROY, NEW YORK.

DESIGN FOR A HEATING-STOVE.

Specification forming part of Design No. 6,316, dated December 17, 1872.

To all whom it may concern:

Be it known that we, NICHOLAS S. VEDDER and FRANCIS RITCHIE, each of the city of Troy, in the county of Rensselaer and State of New York, and TOBIAS S. HEISTER, of Lansingburg, in said county and State, have jointly invented and produced a certain new and original Design for Heating-Stoves, of which the following is a specification, reference being had to the accompanying wood cut or engraving of a stove which embodies our said design.

One part of our invention consists of the design for the part J, as distinguished by the ornamented moldings k and l, shaped and arranged as shown in the aforesaid engraving. Another part consists of the design for the part M, as distinguished by the ornamented molding n and plain molding o, shaped and arranged as shown in the engraving. Another part consists of the design for the rim P, as distinguished by the ornamented molding q and edge r, shaped and arranged as shown in the engraving. Another part consists of the design for the upper section S, as distinguished by the panels t, columns u, and arches v, all shaped and ornamented substantially as shown in the wood-cut. Another part consists of the design for the mica-light frames W, as shown in the engraving. Another part consists of the design for the frame X of the illumination section, as distinguished by the parts y and z, arranged between and over the mica-light frames, and shaped and ornamented as shown in the wood-cut. Another part consists of the design for the rim-plate A, as shown in the engraving. Another part consists of the design for the open-work section B, as shown in the cut. Another part consists of the design for the ash-pit section C, as distinguished by the moldings d and e, shaped, ornamented, and ar-

ranged together as shown in the cut. Another part consists of the design for the bottom plate F, as distinguished by the particular configuration thereof, and the edge-molding g, and ornaments h h thereon, as shown in the cut. Another part consists of the design for the ash-pit cover or hearth-plate I, as distinguished by the ornamented moldings j and K, shaped and arranged thereon as shown in the engraving. Another part consists of the design for the leg L, as shown in the cut.

What we claim as our invention is—

1. The design for the part J, as above set forth.
2. The design for the part M, as described.
3. The design for the rim P, as set forth.
4. The design for the upper section S, as described.
5. The design for the mica-light frames W, as shown and described.
6. The design for the frame X of the illuminating section, as herein set forth.
7. The design for the rim-plate A, as set forth.
8. The design for the open-work section B, as set forth.
9. The design for the ash-pit section C, as described.
10. The design for the bottom plate F, as set forth.
11. The design for the ash-pit cover I, as described.
12. The design for the leg or legs L, as shown and described.

NICHOLAS S. VEDDER.
FRANCIS RITCHIE.
TOBIAS S. HEISTER.
